DESIGN FOR A LIGHTING FIXTURE OR SIMILAR ARTICLE

Henry G. Alm, Elkhart, Ind., assignor to The Adlake Company, a corporation of Illinois

Application July 18, 1938, Serial No. 78,564

Term of patent 14 years

To all whom it may concern:

Be it known that I, Henry G. Alm, a citizen of the United States of America and resident of Elkhart, county of Elkhart, and State of Indiana, have invented a new, original, and ornamental Design for Lighting Fixture or Similar Article, of which the following is a specification, reference being had to the accompanying drawing, forming a part thereof, wherein

Fig. 1 is a side elevational view of a lighting fixture or similar article showing my new design; Fig. 2 is a bottom plan view of the same; and

Fig. 3 is an end view of the lighting fixture.

The dominant features of the design reside in the portions shown in solid lines.

I claim:

The ornamental design for a lighting fixture or similar article, as shown and described.

HENRY G. ALM.
